William D. Krass, Chicago, Ill.

Application October 9, 1944, Serial No. 115,696

Term of patent 14 years

(Cl. D44—10)

To all whom it may concern:

Be it known that I, William D. Krass, a citizen of the United States, residing at Chicago, in the county of Cook and State of Illinois, have invented a new, original, and ornamental Design for a Combined Coaster and Tray, of which the following is a specification, reference being had to the accompanying drawing, forming a part thereof.

The figure shows a perspective view of a combined coaster and tray embodying my design.

I claim:

The ornamental design for a combined coaster and tray, substantially as shown.

WILLIAM D. KRASS.
